(57) **CLAIM**

The ornamental design for a call button bracket, as shown and described.

DESCRIPTION

FIG. 1 is a front perspective view of a call button bracket, in accordance with an embodiment;

FIG. 2 is a rear perspective view of the call button bracket of FIG. 1;

FIG. 3 is a front view of the call button bracket of FIG. 1;

FIG. 4 is a rear view of the call button bracket of FIG. 1;

FIG. 5 is a top view of the call button bracket of FIG. 1;

FIG. 6 is a bottom view of the call button bracket of FIG. 1;

FIG. 7 is a left side view of the call button bracket of FIG. 1;

FIG. 8 is a right side view of the call button bracket of FIG. 1;

FIG. 9 is a rear perspective view of a coupling bracket of the call button bracket of FIG. 1;

FIG. 10 is a front view of the coupling bracket of FIG. 9;

FIG. 11 is a rear view of the coupling bracket of FIG. 9;

FIG. 12 is a top view of the coupling bracket of FIG. 9;

FIG. 13 is a bottom view of the coupling bracket of FIG. 9;

FIG. 14 is a left side view of the coupling bracket of FIG. 9;

FIG. 15 is a right side view of the coupling bracket of FIG. 9;

FIG. 16 is a perspective view of an S bracket of the call button bracket of FIG. 1;

FIG. 17 is a front view of the S bracket of FIG. 16;

FIG. 18 is a rear view of the S bracket of FIG. 16;

FIG. 19 is a top view of the S bracket of FIG. 16;

FIG. 20 is a bottom view of the S bracket of FIG. 16;

FIG. 21 is a left side view of the S bracket of FIG. 16;

FIG. 22 is a right side view of the S bracket of FIG. 16;

FIG. 23 is a front view of a call button bracket in use; and,

FIG. 24 is a rear view of a call button bracket in use.
The broken lines in the drawings of FIGS. 23 and 24 illustrate an environment only and form no part of the claimed design.
